United States Patent Office

Des. 203,105
Patented Dec. 7, 1965

203,105

BUILDING

David E. Termohlen, 1972 Irvine Blvd., Tustin, Calif.

Filed Dec. 14, 1964, Ser. No. 83,028

Term of patent 14 years

(Cl. D13—1)

Des. 203,105

PAGE 2

FIG - 3

The side of said building not shown has substantially the same appearance as the side shown in the figures.

I claim:

The ornamental design for a building, substantially as shown and described.
